UNITED STATES PATENT OFFICE.

JOHN GRIESINGER, OF LOS ANGELES, CALIFORNIA.

BOOK-SEWING MACHINE.

1,266,793.

Specification of Letters Patent. Patented May 21, 1918.

Application filed August 17, 1915. Serial No. 45,994.

To all whom it may concern:

Be it known that I, JOHN GRIESINGER, a citizen of Germany, residing at Los Angeles and State of California, have invented a certain new and useful Book-Sewing Machine, of which the following is a specification.

My invention relates to a book sewing machine, particularly for carrying out the method of sewing disclosed in my patent of April 21, 1914, No. 1,093,694.

An object of this invention is to provide a machine in which the leaves or signatures making up a book may be sewed at a point inward from the edge thereof and at an angle thereto, whereby successively to join said leaves or signatures or a number of them to previously sewed leaves or signatures, in a continuous manner, without the necessity of penetrating a great number of leaves or signatures and to produce by this method a sewed book capable of longer service and harder usage than books sewed in the ordinary way.

Another object of my invention is to provide a machine in which the stitches may be made out of alignment with each other or regularly staggered during the sewing of the leaves or signatures in the making of a book, in order to strengthen the book and avoid the passage of the needles with the thread through or too near previous stitches.

With these and other objects in view, this invention consists of the features and parts, separately and in combination described in the subjoined specification, in connection with the accompanying drawings, and then more specifically pointed out in the claims.

In the drawings,

Figure 1 is a plan view.

Fig. 2 is a front view, showing the clamp for the signatures or sections and the operating means therefor.

Fig. 3 is a side elevation.

Fig. 4 is a plan of the four step cam groove for staggering the stitches.

Fig. 5 is a fragmentary detail showing the swivel connection with the plate.

Fig. 6 is a rear view.

Fig. 7 is an enlarged fragmentary sectional view showing the operative position of the clamp and the operating cam therefor; the inoperative position of the punch and needle bars, and the operating cams

therefor; and the inoperative position of the shuttle race.

Fig. 8 is an enlarged fragmentary view showing the operative position of the needle bar, when the needles are retracted to form loops; and the operative position of the shuttle race and carrier.

Fig. 9 is a fragmentary plan view of the shuttle race partly broken to show the shuttle and shuttle carrier.

Fig. 10 is a section on line 10—10 Fig. 9, looking in the direction of the arrow.

Fig. 11 is a fragmentary end view showing the shuttle race and one of the hangers.

Fig. 12 is a series of perspective illustrations showing the steps followed in the sewing together of four signatures or sections and the staggering of the stitches.

Fig. 13 is a series of end views showing the location of the stitches in building up a book, and

Fig. 14 is a diagrammatic view illustrating the relative arrangement of stitches as made by this machine.

The process of sewing the signatures or sections in the building up of a book according to my invention involves and may be divided into the following steps: clamping the signatures or sections; punching; sewing; locking the sewing thread, and taking up the slack of the latter, each step being accomplished consecutively in the manner and by the coördinated mechanisms shown in the drawings and described *seriatim* hereinafter.

In a frame 1, is a stationary shaft 2, which extends through apertured lugs 3, integral with and projecting from an inclined plate 4, slideable on said shaft and movable about the axis thereof as and for purposes hereinafter appearing.

The plate is supported in its inclined position, as shown in the several views of the drawings, by a rail 5, mounted in said frame. The plate 4, is formed with oppositely disposed walls 6, having ways 7, in which a clamp table 8, is slideable. To the clamp table 8, is connected an operating bar 9, that extends between friction linings 10 and 11, interposed between a presser plate 12 and a base 13, respectively, the presser plate being adjustable on said base and arranged to be clamped by an eccentric lever

14, on one side thereof and connected to a draw rod 15, fastened to and extending through the base and presser plate to effect a quick movement of such plate relatively to its base after adjustment of the bar and its connected table. The base is slidably mounted in ways 16, formed on said plate 4, extends through a slot 17, in said plate, and is slidably connected with a shaft 18, supported by two spaced arms 19 and 20, of a bell crank sleeve 21, by a link 22. The bell crank sleeve 21, is mounted and oscillable on said shaft 2, but held against longitudinal movement thereon by pins 23 and 24, in the shaft. The arm 25, of the bell-crank sleeve 21, is connected by a link 26, with a lever 27, on a fulcrum shaft 28, mounted in the frame 1, the free end of said lever 27, carrying a roller 29, normally bearing against the face of a cam 30, keyed or otherwise secured on a drive shaft 31. Adjustably disposed above said table 8, is a clamp head 32, provided with rods 33, which extend through lugs 34, and 35, on the outside of said walls 6, the lower ends of said rods being threaded to receive nuts 36 and 37, the former being above the lugs 35, and the latter below the lugs 35, and serving to lock the clamp head in adjusted position. A shelf 38, is adjustably mounted on rods 39, rigid with the table 8, and extending through guide bosses 40, on the plate 4, a set screw or other device 41, securing the shelf 38, in position of adjustment. This shelf 38 is movable with the table 8 and is provided for the purpose of temporarily carrying the last series of sewed sections while the threads are still uncut. In this manner the threads are held during the sewing of the successive sections.

40 Between the clamp head 32 and table 8, are placed the signatures or sections to be sewed. The revolving cam 30, through its connections as described, operates the base 13, against which the bar 9, is held by the presser plate 12. The bar 9, and table 8, now move with the base 13, and clamp the signatures preparatory to sewing. In each movement of the table, to clamp an added signature or section with those already sewed the bar 9, moves down relatively to the friction linings 10 and 11, and in this manner a constant pressure is maintained on the signatures or sections in the building up of a book, regardless of the variations in thickness of the signatures or the placement of an excess number in the clamp. As seen, the edge of the plate 4, lies in the operating zone of the punches and needles, the distance in which the edges of the signatures or sections lie with respect to the punches and needles determining the distance of the stitches from the edge. For this reason, the clamp head is made adjustable in the manner described and it is obvious that if the

head is raised with respect to the table, the distance of the signature edges in the operating zone of the punches and needles will be increased, and vice versa.

In the sewing of a book, according to my invention, the entrance point of the needles is near the edges of the separate signatures. Ordinarily the next succeeding stitch would then occur at a point removed from and above the preceding stitch, and would extend in the perforation made by a previous stitch, which would weaken the hold of the paper on the thread. To avoid this, the plate 4, is movable on the shaft 2, after each stitch by the following mechanism shown in Figs. 1 and 5, and the resulting location of the stitches being shown in Fig. 14.

Swiveled onto one of the lugs 3, of the plate 4, and onto the end of a lever 42, is a rod 43. The lever 42, is fulcrumed in a suitable support 44, and is provided on its free end with a stud 45, extending in the four step cam groove 46, of a cylinder 47, which, through the lever 42, imparts at regular intervals a predetermined movement to the plate 4, in substantially the manner and for the distances presently described. This cylinder 47, and a gear 48, are mounted on a stub shaft 49, fixed in the frame 1. Meshing with said gear 48, is a pinion 50, on and revolvable with the drive shaft 31, the ratio between the gear 48 and pinion 50 being as 1 to 4, whereby four complete revolutions of the pinion 50, will cause one complete revolution of the gear 48, which produces four distinct movements of the plate with a determinate interval of time between each movement. Thus the cam groove 46 is formed with four offsets *a*, *b*, *c* and *d*, the offsets *b* and *d*, being approximately one and a half times longer than the offsets *a* and *c* whereby the third stitch and the fifth or initial stitch of the following series will be made at a point removed approximately one and a half time the distance between the first and second stitch. The fourth stitch will then occur at a point between the third and near, the second stitch, as substantially shown in Fig. 14.

The edge of the plate 4, is formed with a plurality of spaced fingers 51, which support the signatures or sections at their edges, and between which the punches and needles operate. The edge of the table 8, is provided with a plurality of grooves 52, in register with the spaces between the fingers 51, the bottom of said grooves lying in a plane parallel with the operating plane of the punches and needles and affording passage for the punches and needles at the outset or beginning of a sewing operation when the table is near the edge of the fingers 51, and the clamp head.

The frame 1, is provided with slide ways

53, for a cross head 54, vertically reciprocable by mechanism presently described. On the upper cross member 53', of the cross head is fastened a bar 55, carrying a plurality of punches 56, which are adjustable therein by thrust screws 57, and held in place by set screws 58. These punches extend into orifices in a guide and stripper plate 59, supported by a plurality of rods 60, which are secured thereto and extend through the punch bar 55, the stripper plate 59, being held in position illustrated in Figs. 6, 7 and 8, by a plurality of helical tension springs 61, surrounding said rods 60, and lying in sockets 62, in the punch bar. On the ends of the rods 60, are placed nuts 63, for adjusting the rods 60, and the connected stripper plate 59, lock nuts 64, being used to secure the nuts 63. On the cross member 53'', 15 of the cross head 54, is fastened a bar 65, carrying a plurality of needles 66, which are adjustable therein by thrust screws 67, and held in place by set screws 68. These needles 66, as seen, are disposed immediately beneath and in the same plane as the punches 56, whereby the needles will enter the perforations made by the punches. The lower cross member 53'', of the cross head 54, is provided with a central extension 69, connected by a link 70, with the end of a lever 71, fulcrumed on the shaft 28, and formed with two arms 72 and 73. The arm 72 is provided on one side with a roller 74, which lies upon the top face of a cam 75, fixed on the shaft 31, and the arm 73, is provided with a roller 76, which lies upon the bottom face of a complementary cam 77, also fixed upon the drive shaft 31, the cams 75 and 77, working in conjunction to reciprocate the cross head 54, and successively produce the following operations:

Assuming that the shaft 31, has been set in motion, and that the positions of the cams 75 and 77, and the parts operatively dependent upon the same, are as shown in Fig. 7, the cross head 54, will move downwardly, causing the punches 56, to perforate the edges of the signatures X, which just previous to the operation of the cams 75 and 77, have been clamped by the operation of the cam 30, as hereinbefore described. Thereupon the cross head 54, is forced upwardly by the complementary cam 77, thereby leaving the springs 61, free to move the stripper plate 59, which, during the downward movement of the cross head 54, moved relatively to the punches during the punching operation, and now under the tension of the springs 61, strips the signatures from the punches. The needles 66, previously supplied with thread from a plurality of spools 78, then enter and pass through the perforations made by the punches and are returned for a short distance to form loops,

whereupon a period of rest intervenes to permit a lock thread to be drawn through said loops and the loop thread to be taken up by the mechanism and in the manner herein-after described. Thereupon the cross head returns to normal position, while the roller 29, on the lever 27, entering the depression in the cam 30, releases the clamp head 8, at which time another signature is inserted for sewing onto those previously sewed. Immediately upon the full release of the pressure of the clamp head 8, on the signatures, the plate 4, is moved by the four step cam groove in the manner and for the purpose above set out. During the period of rest after the formation of the loops, a lock thread 79, is drawn through the loops by a shuttle 80, shown in Fig. 9, and operating in a shuttle race 81, comprising an angle bar 82, and a rectangular bar 83, rigidly secured to hangers 84 and 85, respectively, extending between and holding them spaced at their ends, these hangers being pivotally hung from a rail 86, on the frame, and under the tension of springs 87 and 88, respectively, which function to throw the shuttle race 81, into operative position, as shown in Fig. 8. The rectangular bar 83, on which the shuttle 80, travels, is spaced from the vertical wall of the angle bar 82, as shown, to permit the lock thread to be drawn through such space, and the vertical wall and horizontal wall forming such angle bar 82, are provided with cut out portions 89, for the accommodation of the loops. Extending on the shuttle race 81, is a carrier 90, pivotally hung from a carriage 91, slideable on rail 86, the carrier 90, under the tension of a spring 92, which holds the same in the shuttle race and in engagement with the shuttle 80, as shown in Fig. 9. The carriage 91, is provided with a pin 93, for the accommodation of a forked elongated arm 94, of a bell crank lever 95, pivotally supported in a suitable support 96. The other arm 97, of said bell crank lever is provided with a threaded socket into which a threaded adjusting rod 99, screws, and which rod is held in adjusted position by a lock nut 100. Said rod 99, is connected by a ball and socket joint 101, to a link 102, which latter in turn is connected by a ball and socket joint 103, to a lever 104, fulcrumed on the stub shaft 49. On the end of the lever 104, is a stud 105, extending in a cam groove 106, in a cylinder 107, fixed on the drive shaft 31. Through this cam groove 106 motion is imparted to said lever, which in turn causes a periodical to and fro movement of the elongated arm 94, of the bell crank lever, and consequently also of the shuttle 80. The lock thread 79, paid out from a spool 108, and passing through a suitable tension device, is passed through an eye 109, in the rail, and through one of

the eyes 110, in the shuttle race 81, a plurality of which eyes 110, are provided as shown in Fig. 9, to bring the lock thread in proper relation to the loops of signatures of varying lengths. The stroke of the arm 94, is adjustable by the arrangement described, in accordance with the number of needles in operation.

On the cross head 54, and near the cross member 53', is a lug 111, provided for engagement with an abutment 112, on the shuttle race 81, thereby to throw and hold the race out of the path of movement of said cross head during the punching operation. 10 When the lug 111, escapes engagement with the abutment 112, as it will when the cross head moves upwardly to force through the needles and returns for a short distance to form the loops, the shuttle race 81, under the tension of the springs 87 and 88, will be projected into the position shown in Fig. 8, the loops L extending in the cut out portions 89. At this time the shuttle 80, is operated to draw through the lock thread, the operative position of the shuttle being shown in 15 Fig. 9.

The shuttle is formed with a forwardly curved nose 80', and rearwardly with a taper, the apex 80'', of which lies in a plane 20 removed from the lock thread, whereby on the return of the shuttle to normal or initial position, the thread, which extends through one of the eyes 110, in the shuttle race, will be forced to pass between the edge of the shuttle and the vertical wall of the angle bar 82, after which, it is in a direct line with the hook 80''', of the shuttle. The shuttle moving along the shuttle race with the lock thread caught therein, travels 25 through the loops L, the thread forming which, being now between the outer edge 40 of the shuttle and the carrier 90.

When the shuttle has carried the lock thread through the loops, the cross head 45 descends, pulling through the needles and simultaneously throwing out the shuttle race to the position shown in Fig. 7, with the lock thread still caught in the hook 80''', of the shuttle.

50 The shuttle, shuttle race and needles remain in this position until the take up has operated. Thereupon the shuttle is returned to normal position, and in so doing, drops the lock thread.

55 The threads 78', from the spools 78, as stated, pass through suitable tension devices, thence over a stationary rod 113, carried in hangers 114, on the frame 1, thence under a take up bar 115, carried by two arms 116 60 and 117, fixed on a spindle 118. The arm 116, is formed with an extension 119, in the end of which is journaled a roller 120, bearing against the face of a cam 121, fixed on the shaft 31, and operating to move the take

up bar, at the time set forth above. On 65 the drive shaft 31, is a driving pulley 122, for transmitting power from a suitable source to the shaft, through a suitable trip controlled by a foot pedal 123.

The thread 79, is positioned so that the 70 shuttle will catch and carry same through a subsequent series of loops, by the taking up of the loop threads of the first stitches of the series. Such taking up brings the 75 lock thread upon the surface of the signatures X. The lock thread, running from the eye 110 to near the first needle stitch of the series, occupies substantially a diagonal position in the race, thus crossing the path of travel of the shuttle in the race, as seen in 80 Fig. 9.

From Figs. 12, 13 and 14, it will be seen that after the first signature has been sewed, the second signature is sewed onto the first; the third onto the first and second, and the 85 fourth onto the second and third, and that each successive stitch is made at a point laterally removed from the preceding one in one direction, with the exception that the fourth is made at a point laterally removed 90 from the third stitch in another direction, the appearance of the stitches being substantially zig zag.

What I claim, is:—

1. In a book sewing machine, a plurality 95 of needles, a shaft, a plate on said shaft, a clamp table for the book sections operable on said plate and inclined to the horizontal to bring the edges of the section within the operating plane of and at an angle to the 100 needles, a clamp head on said plate and adjustable relatively to said clamp table, means to operate said clamp relatively to said plate, means to operate said needles, and means to move periodically said plate 105 on said shaft.

2. In a book sewing machine, means to 110 clamp the book sections at an angle to the horizontal; a plurality of vertical needles operable in one direction to pass through the section and periodically in another direction to form loops and withdraw the needles through the sections, a shuttle race, a shuttle in said race, means to move the shuttle to hook the thread and carry same 115 through the loops, means to move the shuttle race out of the operating plane of the needles during the withdrawal thereof through the sections, and means to control all the means in the order named.

3. In a book sewing machine, means to 120 clamp the book sections at an angle to the horizontal, a plurality of vertical needles operable in one direction to pass through the sections and in another direction for a 125 limited distance to form loops, a shuttle race, a lock thread passing therethrough, a shuttle in said race, means to move the shut-

- tle to hook the thread and carry same through the loops, means to control all said means in the order named, and means to regulate the distance of the travel of said shuttle. 5 means operable over and longitudinally relative to the signatures to provide a lock thread for the stitches, and means to move said clamp table and signatures relatively to the stitch forming mechanism after each stitch. 65
4. In a book sewing machine, a frame, a clamp thereon to hold the book sections thereon at an angle to the horizontal, a cross head operable in said frame and carrying a 10 punch and a needle bar, a plurality of punches and needles, respectively, in said punch and needle bar, means to operate said cross head to cause the punches to perforate the sections, the needles to enter the per- 15 forations and to be retracted to form loops, a shuttle race on said frame, a lock thread passing therethrough, a shuttle operable in said race to hook the thread and carry same through the loops, means operable by the 20 movement of the cross head in one direction to throw and hold said shuttle race out of operative position and in another direction to cause said race to be thrown into operative position, and means to control all said 25 means. 70
5. In a book sewing machine, a stitch forming mechanism for signatures, a clamp table supporting the signatures, a clamp head co-operating with said clamp table, means to hold said clamp table in position for a pre- 30 determined pressure whereby to enable said table to move relatively to said holding means, and means to operate said clamp table automatically relatively to said clamp 35 head. 75
6. In a book sewing machine, a stitch forming mechanism for signatures, a clamp table to support the signatures at an angle to the horizontal, a clamp head co-operating 40 with said clamp table, means to hold said clamp table in position during a predetermined pressure whereby to enable said table to move relatively to said holding means when said pressure is exceeded, means to 45 regulate said pressure and means to operate said clamp table automatically. 80
7. In a book sewing machine a punching mechanism for the signatures and a stitch forming mechanism, a clamp table to support the signatures at an angle to the horizontal, a clamp head co-operating with said clamp table, means to operate said clamp table automatically to clamp or unclamp the signatures, and means to move said clamp 55 table laterally relatively to the stitch forming mechanism after each stitch. 85
8. In a book sewing machine, a punching mechanism for signatures, and a stitch forming mechanism, a clamp table to support the signatures at an angle to the horizontal, a clamp head co-operating with said clamp table, means automatically to operate said clamp table, means to operate said punching and stitch forming mechanism, 60 means to hold said clamp table in position for a predetermined pressure whereby to enable said table to move relatively to said holding means, and means to operate said clamp table automatically to clamp or unclamp the signatures, and means to move said clamp table laterally relatively to the stitch forming mechanism after each stitch. 90
9. In a book sewing machine, a stitch making mechanism for signatures, a clamp table supporting the signatures, a clamp head co-operating with said clamp table, means to hold said clamp table in position for a predetermined pressure whereby to enable said table to move relatively to said holding means, means to operate said clamp automatically, and a means to move said clamp periodically laterally to cause the 95 stitches to be made out of alinement with each other. 100
10. In a book sewing machine, a plurality of punches and needles, a clamp table to support the signatures in line with the travel of and at an angle to said punches and needles, means to provide a lock thread for the loops formed by said needles comprising a race, operable over the edges of the signatures, a thread passing through said race, a shuttle operable in said race to catch and draw the thread through all of the needle loops, means to operate said shuttle, and means to operate said punches and needles. 95
11. In a book sewing machine, a plurality of punches and a plurality of needles, a means to support signatures in line with said punches and needles and at an angle thereto, means to operate said punches and needles and means to move said supporting means periodically laterally to cause each series of stitches to be made at predetermined various distances from and out of alinement with each previous series. 100
12. In a book sewing machine, a plurality of punches and needles, a clamp table to support signatures to be sewed at an angle to said punches and needles, means to operate said clamp table automatically, means to operate said punches and needles, means movable longitudinally over and relatively to the signatures to draw a lock thread through the loops formed by the needles, and means to move said clamp table for 115 irregular distances to cause the stitches to be made out of alinement. 110
13. In a book sewing machine, a stitch forming mechanism for signatures, a clamp table to support the signatures at an angle to the horizontal, an adjustable clamp head co-operating with said clamp table, means to operate said clamp table, and means to hold said table stationary during a predetermined pressure, said means enabling said table to move relatively to said clamp head when such pressure is exceeded. 120
14. In a book sewing machine, a stitch

forming mechanism for signatures, a clamp table to support the signatures at an angle to the horizontal, an adjustable clamp head coöperating with said clamp table, means to 5 operate said clamp table, means to hold said clamp table stationary during a predetermined pressure, said means enabling said table to move relatively to said clamp head when such pressure is exceeded, and means

to regulate said holding means to predetermine the pressure.

In testimony whereof I affix my signature in the presence of two witnesses.

JOHN GRIESINGER.
